UNITED STATES PATENT OFFICE.

WINGATE S. THOMAS, OF CHICAGO, ILLINOIS, ASSIGNOR TO KNAPP BROTHERS MANUFACTURING COMPANY, OF CHICAGO, ILLINOIS, A CORPORATION OF ILLINOIS.

BUILDING CONSTRUCTION AND THE LIKE.

Application filed November 26, 1923. Serial No. 677,127.

To all whom it may concern:

Be it known that I, WINGATE S. THOMAS, a citizen of the United States, residing at Chicago, in the county of Cook and State 5 of Illinois, have invented certain new and useful Improvements in Building Constructions and the like, of which the following is a specification.

This invention has to do with certain improvements in building constructions and the like. The invention has reference particularly to improvements in the construction of base boards and similar running strips. The invention has reference particularly to improvements in the form and construction of the fitting used at corners and other special places where the direction of the running strip is changed.

More particularly the invention has to do with improvements in fittings of the above general class which are made of metal. It has been the practice in the past, where metal base boards and similar running strips are used, to provide special castings 25 or similar cumbersome fittings at the corners or where the direction is to be changed. These castings are objectionable from a number of standpoints including weight and bulk as well as relatively high cost of 30 manufacture.

The main object of the present invention is to provide corner or other angle fittings of a very simple form which may conveniently be made of sheet metal stamped or 35 pressed into the desired form.

In connection with the foregoing, it is a further object of the invention to so form and arrange these fittings that when they are set into place with the base boards or 40 other running strips, and when the walls and floor of the building construction are completed, the exposed surfaces will be substantially continuous and flush at all points, and present a pleasing and slightly appear- 45 ance.

More particularly it is an object of this invention to make provision for convenient connection of the base boards or running strips to the corner or angle fittings themselves, taking into account the form and construction of certain metal base board types which are extensively in use at this time. In this connection it is a further object to provide for very simple and conven-

ient attachment of the end portions of the 55 base boards, etc., to the fitting by the use of bolts, nails, screws or other convenient attaching devices and without the necessity of providing special attaching means.

Still more particularly it is an object of 60 the invention to provide for the flush attachment of the base boards or running strips with the fittings so as to establish the flush exposed surfaces previously referred to, while at the same time giving adequate 65 support to the back side of the end portions of the base boards, etc. This idea incorporates the feature of providing an offset in the edge portion of the fitting of the proper depth to accommodate the thickness of the 70 base board or the like. In the present application I have disclosed constructions in which this offset portion is provided particularly by the use of flanges which are attached to the edge portions of the fitting 75 itself, said flanges being formed separate and independent of each other.

Other objects and uses of the invention will appear from a detailed description of the same, which consists in the features of 80 construction and combinations of parts hereinafter described and claimed.

In the drawings:

Figure 1 shows a perspective view of an inside corner fitting embodying the features 85 of the present invention and having applied to one edge thereof the end portion of a strip of base board, the other edge of the fitting being exposed before the application of the base board strip thereto;

Fig. 2 shows a perspective view, broken away in its central portion, showing the form of the fitting plate illustrated in the combination of Fig. 1;

Fig. 3 shows a perspective view of one 95 of the flange plates used in the combination of Fig. 1, being the left hand flange plate;

Fig. 4 shows a side elevation corresponding to Fig. 1, the base board strip not being 100 in place;

Fig. 5 shows a top plan view corresponding to Fig. 4;

Fig. 6 shows a bottom plan view corresponding to Fig. 4;

Fig. 7 shows a rear perspective view of 105 a modified form of fitting embodying the features of the present invention, the same

being for use on an external corner, and showing the end portion of one base board strip in place;

Fig. 8 shows a perspective view of the fitting plate of the form shown in Fig. 7;

Fig. 9 shows a perspective view of one of the side flange plates of the form shown in Fig. 7;

Fig. 10 shows a side elevation of the form shown in Fig. 7 without the presence of the base board strip;

Fig. 11 shows a top plan view corresponding to Fig. 10; and

Fig. 12 shows a bottom plan view corresponding to Fig. 10.

Referring first to the form shown in Figs. 1 to 6, inclusive, and more particularly in Fig. 1, the end portion of one of the base board strips is designated by the numeral 15. It is of standard construction, and includes the vertical body portion 16 whose lower end portion 17 is generally curved outwardly on a smooth sweep to a point where it lies practically tangent to the floor surface. The extreme lower edge portion 18 is turned straight down so as to stand in a vertical position. The upper portion of the strip 15 is generally deflected back on a sharp angle, as shown at 19, for substantially the thickness of the plastering, and the extreme upper edge 20 is turned up into a vertical position, as shown in Fig. 1.

The result of the foregoing is that the flanges 18 and 20 may be set or attached solidly to suitable nailing strips or the like so as to hold the base board rigidly in place. When the plastering is completed it comes down substantially flush with the upper edge of the body portion 16, and when the floor is laid into position it comes practically flush with the edge of the curved portion 17. In this way a practically continuous flush connection is established between the surface of the floor and the surface of the wall.

The fitting of the present invention, whether used for an internal or an external angle, is intended to establish a flush connection with the end portions of the base boards or other running strips and at the same time provide a firm and rigid connection thereof with the walls or other permanent structure.

In the forms herein illustrated, the angles are 90°, but manifestly the features of the invention may also be used for joining up either sharper or easier angles.

Where an inside angle is to be fitted, there is provided a fitting plate 21. This has the side vertical wings 22 and 23 which are intended to contact the end portions of the base board or like strips, and the lower portion of the fitting plate is dished outwardly on regular curves, as shown at 24, so that its two edges 25 and 26 will properly register with the edges of the base board

or like strips clear down to the point where the same become tangent to the floor surface. In the case of a right angle inside fitting, the wings 22 and 23 lie at right angles to each other and the lower portions of the edges 25 and 26 will approach each other at points somewhat removed from the point 27 which represents the exact center of the curve on which the lower portion 24 is dished. I, therefore, in such cases provide a notch 28 in the lower central portion of the fitting so as to establish the edge 29 in direct registry with the lower flanges 18 of the base board strips when in place. The relationship of the parts when assembled will be readily understood from examination of Fig. 1.

At each side of the fitting plate 21 there is secured a flange strip 30 which projects beyond the fitting plate a distance sufficient to provide for rigid attachment to the end portions of the base boards. Each of these strips 30 has the body portion 31 whose lower end is curved outwardly as shown at 32 and provided with an extreme depending flange 33. The body 31 and the curved portions 32 are intended to seat snugly against the back side of the fitting plate 21.

Owing to the fact that the edge portions of the fitting plate are carried out a certain distance of tangency with respect to the base boards, the flange plates 30 can be set against these tangential edge portions and spot welded or otherwise secured thereto so as to provide the structure clearly illustrated in Fig. 1.

The upper end of the flange plate 30 is bent backwardly at right angles, as shown at 34, and its extreme end is then turned up again, as shown at 35. The flange plate is also notched as shown at 36 at the point where the rearward bend 34 takes place. This notching is so formed that whereas the body portion 16 of the base board lies against the front surface of the flange plate 30, the upper flange 19 of the base board passes through the slot 36, and the flange 20 of the base board lies flush against the back side of the lug 35. This arrangement makes it possible for the base board flange 20 to maintain its snug fit against the permanent structure throughout its length, and still establish the desired relationship of the parts at the point where the base board and corner fitting come together.

It will be understood that the thickness of the fitting plate is intended to be the same as that of the base board material, so that a flush exposed surface will be presented.

The form shown in Figs. 7 to 12 inclusive is intended for use with an external angle. In this case the fitting plate 37 has the vertical side portions 38 and 39, joined together on the desired curvature, the lower

portion of the fitting 37 being dished outwardly as shown at 40 in order to bring its edge portion into tangency with respect to the floor level. In this construction the 5 flange plates 41 are similar to those particularly described in connection with the previous connection, and when the base boards are set into place similar relationships are established. In like manner the flange 10 plates 41 may be secured to the fitting plate 37 in any convenient manner as by means of spot welding or otherwise.

I wish to point out the fact that in the constructions herein particularly illustrated 15 the pairs of flange plates 30 and 41 respectively are separate from each other and are intended for independent attachment to the fitting plates. Nevertheless, the features of the invention may also be embodied in other 20 constructions, as, for example, constructions in which these flange plates are formed as a unit and from a single piece of sheet metal. I do not, however, specifically claim such construction in this application, since the 25 same constitutes the subject-matter of another application for Letters Patent of the United States executed by me of even date herewith.

While I have herein shown and described 30 only certain embodiments of the features of my present invention, still I do not intend to limit myself to the same, except as I may do so in the claims.

I claim:

35 1. In a building construction the combination with a metal base board in the form of a sheet metal strip having a vertical body portion, and an outwardly curved quarter round at its lower end adapted to establish tangent connection with the floor surface, the upper edge of the body portion being adapted to establish flush connection with the wall surface, of a sheet metal angle fitting adapted to fit onto the end of the 40 base board strip and establish a continuous exposed surface flush with the exposed sur-

face of the base board strip throughout the line of junction between the wall and floor surfaces, said fitting comprising a fitting plate of thickness equal to that of the base 50 board strip and having a vertical body portion whose sides come together on the desired angle or curvature and whose lower portion is formed on a curved surface of which the lower edge portion terminates at 55 every point substantially tangent to the surface of the floor, together with outwardly projecting flanges extending along the edges of the fitting strip and set rearwardly with respect to the exposed surface of the fitting a 60 distance substantially equal to the thickness of the base board strip, the upper edge of the fitting plate lying substantially on a level with the upper edge of the base board strip, whereby a flush substantially continuous surface is established between the base board strip and the fitting plate at all points 65 between the wall and floor surfaces aforesaid, substantially as described.

2. As a new article of manufacture, a 70 sheet metal angle fitting adapted for use in conjunction with a sheet metal base board strip, said fitting comprising a fitting plate of thickness equal to that of the base board strip and having a vertical body portion 75 having flat sides which come together on the desired angle or curvature and whose lower portion is formed on a curved surface of which the lower edge portion terminates at every point substantially tangent to the 80 surface of the floor and which sides are curved outwardly at their lower ends on a curvature the same as that of the lower portion of the base board, and a flange strip secured against the back face of each side 85 portion of the fitting plate including the lower curved portion thereof and reaching from a point adjacent to the top edge of the fitting plate to a point adjacent to the lower edge thereof, substantially as described. 90

WINGATE S. THOMAS.
